UNITED STATES PATENT OFFICE.

IRVIN Y. BARINGER, OF PERKASIE, PENNSYLVANIA, ASSIGNOR OF ONE-HALF TO THOMAS L. KNEILE, OF PHILADELPHIA, PENNSYLVANIA.

DESIGN FOR A NUT-LOCK OR FASTENER-BAR.

SPECIFICATION forming part of Design No. 29,834, dated December 20, 1898.

Application filed November 17, 1898. Serial No. 696,729. Term of patent 14 years.

To all whom it may concern:

Be it known that I, IRVIN Y. BARINGER, a citizen of the United States, residing at Perkasie, in the county of Bucks, State of Pennsylvania, have invented and produced a new and original Design for a Nut-Lock or Fastener-Bar, of which the following is a specification, reference being had to the accompanying drawings, forming part thereof.

10 The leading feature of my design for a nut-lock or fastener-bar is a bar having on its upper face a slope which extends from the apex of the bar to the inner side thereof.

Figure 1 represents a perspective view of 15 a nut-lock or fastener embodying my design. Fig. 2 represents a section thereof on line xx , Fig. 1, on an enlarged scale.

A designates a bar on whose upper face are the slopes B and C. The slope B extends from the apex D to the inner side E of said 20 bar and the slope C extends from said apex to the outer side F of said bar. In the outer side E are the recesses G.

Having thus described my invention, what I claim as new, and desire to secure by Letters 25 Patent, is—

The design for a nut-lock or fastener-bar substantially as shown and described.

IRVIN Y. BARINGER.
